G. O. MOBLEY

COMBINED STATEMENT AND LEDGER SHEET

Filed June 8, 1926

Inventor
MOBLEY.

G.O. MOBLEY,

B.M. Dickbun

Attorney

UNITED STATES PATENT OFFICE.

GEORGE O. MOBLEY, OF HEATH SPRINGS, SOUTH CAROLINA.

COMBINED STATEMENT AND LEDGER SHEET.

Application filed June 8, 1926. Serial No. 114,548.

My invention relates to a combined statement and ledger sheet, adapted for use with posting machines, which are commonly used in banks.

5 An important object of the invention is to provide means of the above mentioned character whereby the statement work may be carried along with the regular posting, thereby avoiding the work of making up 10 separate statements.

In banks two accounts are frequently run, one for the ledger, and one for the statement. In some banks, a separate statement is made up at the end of the month, 15 which is sent to the depositor. In most banks a statement is rendered to each depositor at the end of each month and these statements are made up exactly as the ledger sheets are but are made up separately.

20 In accordance with my invention, I provide a sheet, which is preferably folded upon itself, producing upper and lower sheets. The upper and lower sheets are preferably substantially identical and are 25 ruled to provide vertical columns or spaces, suitably designated, for receiving the items 30 of the account. These sheets are of the ordinary ledger sheet type. The upper and lower sheets are connected at their point of folding preferably by a line of perforation, and the free ends of these sheets are 35 detachably connected, in a manner which will enable them to lie flat, and partake of 40 restricted relative sliding movement so that they may be passed through the posting machine, without liability of puckering or 45 impeding the operation of the machine. The two sheets are adapted to receive and hold 50 between them a sheet of carbon. The two sheets, constituting the unit, are adapted to be worked in the ordinary posting machine, and the items of the account are typewritten 55 thereon, the original on the top sheet and a carbon copy upon the lower sheet. At the 60 end of the month or at any desired date, the portion of the upper sheet, constituting the statement section, may be torn from the 65 lower sheet, and mailed to the customer, thus indicating to him the condition of his 70 account. The lower sheet, preferably with 75 the original balance strips attached thereto, is preserved in the ledger. In this manner, 80 the statement account and the posting account, both for the customer and for the 85 bank are made at the same time.

In the accompanying drawings, forming

a part of this specification, and in which like numerals are employed to designate like parts throughout the same,

Figure 1 is a plan view of the sheets embodying my invention. 60

Figure 2 is a similar view of the lower sheet, and

Figure 3 is an edge elevation of the device, the free ends of the sheets being 65 separated for the purpose of illustration.

In the drawings, wherein for the purpose of illustration, is shown a preferred embodiment of my invention, the numerals 5 and 6 70 designate lower and upper sheets, which are preferably constructed identical in most respects. These sheets are folded at corresponding ends, upon a line of perforation 7, while they may be secured together by glue, if desired, although it is preferred that 75 the sheets be made from an integral leaf with the line of perforation. Each upper and lower sheet is provided with horizontal lines 8 and 9, and vertical lines 10. The upper sheet 6 is provided with vertical lines 80 of perforation 11. Above the horizontal line 8 on each sheet is a heading space 12, containing the name of the bank, preferably printed thereon, and suitably designated spaces, for filling in the name and address 85 of the depositor, and a brief statement as to his account, at the desired date. Each sheet also has a suitable space 13 for the reception of a number designating the sheets having the same numbers. Between the 90 horizontal lines 8 are spaces, receiving designations 14 and 15, indicating old balance and new balance. These designations are arranged at the head of balance strips 15', 95 which are arranged upon opposite sides of the statement section 16. The statement section 16 of each sheet is provided in the spaces between lines 8 and 9 with designations 17 and 18, indicating the checks in detail, and their dates, and these indicated data 100 are typewritten upon the statement section 16. The statement section also has designations 17' and 18', indicating the deposits and dates thereof, the balance to be listed below by the posting machine. 105

The lower sheet 5 is provided adjacent its lower corners or free ends with upper and lower horizontal slits 19 and 20, for receiving tongues 21 formed upon the balance strips 15' of the upper sheet, by slitting the same, as shown at 22. The tongues 21 are adapted to be inserted through the slits 110

19 and 20 to engage beneath the transverse webs 22, and the two sheets are, therefore, secured together in a flat manner and the connection is flat so that the sheets will not 5 pucker or impair the operation of the posting machine when they are being operated upon by the posting machine. Further, the tongues 21 are adapted to partake of limited longitudinal movement within these 10 slits and hence the sheets may adjust themselves when passing about the roll of the posting machine. A sheet of carbon paper 23 is arranged between the lower and upper sheets 5 and 6 and is held thereby against 15 displacement, particularly displacement in the direction of the free ends of the sheets. The statement section 16 of the upper sheet 6 is preferably shortened, so that it may terminate at the line 16'.

20 The two sheets thus connected are placed in the posting machine, and the usual posting for the ledger is done upon these sheets, the upper sheet receiving the original impression and the lower sheet the carbon 25 impression. When it is desired to send a statement to the depositor, the statement section 16 of the upper sheet is torn along the lines of perforation 11 and the line of perforation 7 and thus separated. This 30 statement section is sent to the depositor. The balance strips 15', preferably remain attached to the lower sheet 5, and are retained in the ledger with the lower sheet. It is to be understood that the form of my 35 invention, herewith shown and described is to be taken as a preferred example of the same, and that various changes in the shape, size and arrangement of parts may be resorted to, without departing from the spirit 40 of my invention or the scope of the subjoined claims.

Having thus described my invention, I claim:—

1. A combined ledger and statement sheet 45 for posting machines, comprising a single section of paper folded transversely upon itself for providing upper and lower sheets, the upper section of paper having perforations at the transverse fold whereby the 50 leading ends of the upper and lower sheets are relatively rigidly and detachably connected to positively prevent relative longitudinal movement between said leading ends, the upper sheet only having longitudinal 55 perforations, which lead to the transverse perforations, the lower and upper sheets being longitudinally ruled for providing an

intermediate statement section and outer side balance strips, the statement section and the strips having proper heading designations, the statement section of the upper sheet being adapted to be torn along the longitudinal and transverse lines of perforations and thereby separated from the lower sheet and balance strips of the upper 60 sheets, and flat means affording a longitudinally sliding connection between the free end of each balance strip and the lower sheet, whereby a sheet of carbon paper may be properly held between the upper and lower sheets and the sheets will not pucker when being rapidly fed through the posting machine, the flat connecting means serving to retain the trailing ends of the balance strips to the lower sheet when the 65 statement sheet is torn therefrom, the balance strips being free from connection with the lower sheet except at the leading and trailing ends.

2. A combined ledger and statement sheet 80 for a posting machine, comprising upper and lower sheets, said sheets having their leading edges detachably and relatively rigidly connected throughout substantially their entire length so that the leading edge 85 of one sheet can not move longitudinally with relation to the other leading edge, the upper sheet only having longitudinal lines of perforations, the lower and upper sheets being longitudinally ruled for providing 90 an intermediate statement section and outer side balance strips, the statement section and the strips having proper heading designations, the statement section of the upper strip being adapted to be torn along the 95 longitudinal line of perforations, the balance strips of the lower sheet being provided adjacent to their trailing ends with transverse slits, and tongues carried by 100 said balance strips of the upper sheet adjacent to their trailing ends and extending longitudinally of the last named balance strips and adapted for insertion within said slits, the upper and lower sheets being free from connection except adjacent to 105 their leading and trailing ends, said sheets being adapted to hold a sheet of carbon paper between them and the tongue and slit connections permitting of the relative longitudinal movement between the upper and lower sheets throughout the entire length 110 rearwardly of their leading edges.

In testimony whereof I affix my signature.
GEORGE O. MOBLEY.
